W. I. HARP.
ENGINE STARTING DEVICE.
APPLICATION FILED FEB. 19, 1917.

Patented Dec. 18, 1917.

FIG. 1.

UNITED STATES PATENT OFFICE.

WILLIAM ISAAC HARP, OF GALAX, VIRGINIA.

ENGINE-STARTING DEVICE.

1,250,449.

Specification of Letters Patent. Patented Dec. 18, 1917.

Application filed February 19, 1917. Serial No. 149,574.

To all whom it may concern:

Be it known that I, WILLIAM I. HARP, a citizen of the United States, residing at Galax, in the county of Grayson and State of Virginia, have invented certain new and useful Improvements in Engine-Starting Devices; and I do declare the following to be a full, clear, and exact description of the invention, such as will enable others skilled in the art to which it appertains to make and use the same.

This invention relates to new and useful improvements in attachments for internal combustion engines, particularly for the starting mechanism thereof.

The principal object of the invention is to provide mechanism of this character which will positively prevent injury to the operator during the cranking of the engine as a result of back-firing.

An additional object is to provide means whereby the starting crank will be automatically disengaged from the crank shaft of the engine immediately upon the back-firing of the latter.

With these and other objects in view, the invention resides in the novel features of construction, combination and arrangement of parts which will be hereinafter more particularly described and claimed and shown in the drawings wherein;

Figure 1 is a perspective view of the front end of an automobile showing my improved attachment applied to the starting crank thereof;

Fig. 2 is a plan view of the device;

Fig. 3 is a front elevation;

Fig. 4 is a central vertical section on the plane of the line 4-4 of Fig. 2;

Fig. 5 is a vertical transverse sectional view;

Fig. 6 is a detail perspective view of the stationary ring; and

Fig. 7 is a similar view of the loop designed to hold the handle of the starting crank.

In the accompanying illustration, in which similar reference characters indicate like parts, the invention is shown applied to an automobile of the Ford type, although it is obvious that it may be used on stationary or marine engines as well as other types of automobile engines.

The device consists broadly of a ratchet mechanism and means for connecting the crank C thereto. In automobiles of the form illustrated, the crank C is journaled in a bearing block B supported between the front cross bar F of the vehicle frame and the bottom of the radiator R, and is detachably connected to the end of the crank shaft S of the engine by means of the ratchet A. The bearing block B is held in place on the front cross bar F by a pair of U-bolts 1 which extend through openings in ears carried by the block and have nuts 2 on their upper ends.

The stationary portion of the ratchet mechanism of the invention is secured by these U-bolts to the front cross bar, and consists of a plate-like ring 3 of any desired diameter which has ears 4 extending from its opposite sides. These ears are preferably formed integrally with the ring 3, they being cut from the metal forming the ring 75 and bent into the proper position, as shown, and are reinforced by the portions 5. In addition to being extended outwardly from the edge of the plate, these ears are also disposed rearwardly of the rear face of the 80 ring so that when the same are attached to the threaded ends of the U-bolts 1, the plate will be spaced outwardly slightly from the bearing block B.

Rotatably mounted within the opening 6 of the stationary or outer ring 3 is an inner ring 7, the outer diameter of which is slightly less than the diameter of the opening 6. This inner ring 7 is provided with a central opening 8 of sufficient size to receive 90 the shank 9 of the crank C. The periphery of the inner ring 7 is formed with a plurality of slits 10 in which are disposed stiff leaf springs 11, the outer ends of the same projecting substantially tangentially from 95 the ring and in the same direction. These springs 11 form dogs for engagement with ratchet teeth 12 cut in the wall of the opening 6 of the stationary ring 3 and thus prevent the rotation of the inner ring except 100 in one direction, and in the present instance a clock-wise direction.

The inner rotatable ring is held in position within the opening in the stationary ring by means of the cover plates 13, one of 105 which is disposed over the inner while the

other covers the outer side of the opening 6, said plates being preferably circular and of a diameter somewhat less than the diameter of the ring 3. A plurality of bolts 14 extend through alined openings in the ring 7 and the plates 13, and hold these parts together. In this manner the inner ring may readily rotate within the stationary ring without danger of its being moved out of operative position. These plates 13 also have central openings 15 alined with the opening 8 in the inner ring for the reception of the portion 9 of the crank C.

A substantially U-shaped yoke or loop 16 carried by the rotatable portion of the ratchet mechanism connects the handle 17 of the crank C thereto, this part of the crank extending through the loop, as illustrated. The ends of the arms 18 and 19 of the loop 20 are screw-threaded and extended through alined openings in the ring 7 and plates 13 and provided with nuts 20, thereby securely attaching the loop to the inner ring and also providing means for aiding in holding 25 said ring and the plates 13 together.

The arm 18 of the yoke is so bent as to form a pair of seats 21 and 22, the former being adjacent the outer plate 13 and is adapted to receive the handle portion 17 of the crank when the latter is being used to start the engine. The inclination of the inwardly bent part 23 of the arm 18 readily holds said crank in the seat 21 while the cranking operation is taking place. As soon, 35 however, as the engine is started and the crank has been released, the usual spring on the shank 9 of the crank will force the same outwardly so as to disengage the ratchet A, whereupon the portion 17 of the crank may 40 rest within the seat 22. When the crank has been disposed in the seat 22 it may be held in any position relative to the ground, since the springs 11 will engage the teeth 12 and hold the rotatable portion of the ratchet 45 mechanism, to which the crank is connected, stationary.

The other arm 19 of the loop is adapted to engage the portion 17 of the crank C when the engine back-fires and to cause the 50 same to be disengaged from the crank shaft S and thereby prevent injury to the operator. In carrying out this function said arm 19 is inclined outwardly from its inner to its outer end relative to the outer plate 55 13. Since the engagement of the springs 11 with the teeth 12 of the stationary ratchet member will prevent the crank from being rotated in one direction, it is obvious that as soon as the crank, which has been caused 60 to move in a counter-clock-wise direction by the back-firing of the engine, has struck the inclined arm 19, the inner end will be disengaged from the crank shaft as above mentioned.

From the foregoing description, taken in connection with the accompanying drawing, it will be seen that a very simply constructed mechanism has been produced which will positively prevent injury as a result of the back-firing of an internal combustion engine 70 when the same is applied to the crank thereof. All of the parts are very simply yet strongly constructed, and may be inexpensively manufactured. The device as designed may be applied to practically any type of internal combustion engine with only a slight modification of the means for positioning the stationary part of the ratchet.

I claim:—

1. The combination with a crank shaft 80 and a starting crank having a detachable engagement therewith, of a ratchet member rotatable in one direction, and a substantially U-shaped loop carried by said member and surrounding the crank, one arm of said 85 loop having a seat to receive the crank when the same is rotated to hold its end in engagement with the crank shaft.

2. The combination with a crank shaft and a starting crank having a detachable engagement therewith, of a ratchet member rotatable in one direction, and a substantially U-shaped loop carried by said member and surrounding the crank, one arm of said 90 loop having a seat to receive the crank when the same is rotated to hold its end in engagement with the crank shaft, the other arm of said loop being inclined outwardly from its inner toward its outer end relative to the member, whereby when said crank 95 is caused to engage the same by the back-firing of the engine, its end will be disengaged from the end of the crank shaft.

3. In a device of the class described, a fixed ring having ratchet teeth on its inner 105 edge, a second and inner ring rotatable within the fixed ring, a dog carried by the inner ring for engagement with the ratchet teeth on the outer ring, plates contacting with the opposite sides of said fixed ring and 110 covering the opening therein, said plates having central openings, means connecting said plates with the inner ring, a crank extending through said central openings in the plates and inner ring, and means for 115 connecting the crank with said inner ring and plates.

4. In a device of the class described, a fixed ring having ratchet teeth on its inner edge, a second inner ring rotatable within 120 the fixed ring, a dog carried by the inner ring for engagement with the ratchet teeth on the outer, plates disposed over each side of said fixed ring and covering the opening therein, said plates having a central opening, means for connecting said plates with the inner ring, a crank extending through said 125 central opening in the plates and inner ring,

a U-shaped loop, the ends of the arms of said loop extending through said inner ring and plates, and nuts on the ends of said arms to secure said loop to the inner ring and plates, to hold the latter together, said loop receiving said crank.

In testimony whereof I have hereunto set

my hand in the presence of two subscribing witnesses.

WILLIAM ISAAC HARP.
